UNITED STATES PATENT OFFICE.

PILADE BARDUCCI, OF NAPLES, ITALY.

DRYING-CHAMBER.

1,248,438.

Specification of Letters Patent. Patented Dec. 4, 1917.

Application filed April 12, 1916. Serial No. 90,649.

To all whom it may concern:

Be it known that I, PILADE BARDUCCI, a subject of the King of Italy, residing at Naples, Italy, have invented certain new and useful Improvements in Drying-Chambers, of which the following is a specification.

This invention relates to a ventilating system in which it is required to produce air streams of continually varying direction and intensity.

According to this invention the above result is attained by using one or more fans revolving around a horizontal axis perpendicular to the axis of rotation of the fan or fans, these fans being arranged preferably in the intermediate portion of the chamber in which said fans are employed.

The accompanying drawings show by way of example some constructions, according to this invention, of a ventilating system for alimentary pastes:

Figure 1 is a longitudinal section of a drying chamber embodying the present invention,

Figs. 2, 3, 4, 5 and 6 show diagrammatically the air streams produced in the chamber during the operation of the fan, some parts of the chambers being omitted from said figures for the sake of clearness,

Fig. 7 is a side view of an apparatus comprising this invention,

Fig. 8 is a longitudinal section of a chamber provided with a modified form of the apparatus,

Fig. 9 is a transverse section of the same, Fig. 10 shows in detail the construction of the apparatus shown in Figs. 8 and 9.

As shown in Figs. 1 to 6, the chamber 1 is provided with supports 2 adapted to carry rods 3 which in turn support the material to be dried. In the middle portion of said chamber between supports 2, is mounted a rotary transverse shaft 4 carrying one or more fans 5 whereof the axes are perpendicular to shaft 4.

The air is removed from the chamber by means of exhausters 8 arranged near the floor at the opposite ends of the chamber, and fresh air, which may be heated if desired, is supplied to the chamber 1 through openings 6 provided in the walls of a duct 7 parallel to and arranged above the shaft 4.

Pipes 9 in which a heated medium is caused to circulate are used to heat the air in chamber 1.

Fig. 7 shows by way of example a construction of apparatus adapted to cause fans 5, 5' to revolve around a horizontal axis. Said apparatus comprises a horizontal shaft 4 pivoted in bearings 10 secured to the walls of the chamber and provided with transverse sleeves 11, 11' securely fixed to said shaft. In the sleeves 11, 11' are pivoted the shafts 38, 38' of fans 5, 5' these shafts being provided with pulleys 39, 39' connected by a belt 12.

The apparatus is operated by means of a pulley 16 and belt driven by a transmission shaft not shown in this drawing. Said pulley is loosely mounted on shaft 4 and is provided with a toothed rim 15 meshing with a pinion 14 and thereby driving a pulley 14' which in turn rotates a pulley 38'' by means of a belt 12', the pulley 38'' being securely fixed to the shaft 38' of fan 5'.

The shaft 38 of the other fan is provided with a worm gear 17 engaging a helicoidal wheel 18 securely fixed to shaft 19, said shaft being pivoted in a bracket 40 secured to the shaft 4. Shaft 4 is provided with a pinion 20 engaging a stationary toothed rim 21 which is secured to the wall of the chamber by means of bolts 41.

When rotated, pulley 16 renders operative the rim 15, pinion 14, pulley 14', belt 12', pulleys 38'' and 39', belt 12, and pulley 39, thus causing shafts 38 and 38' to rotate, while worm 17 rotating the wheel 18 causes pinion 20 to roll on stationary rim 21; the shaft 4 and fans are thus caused to rotate as a whole in bearings 10.

In the apparatus shown in Figs. 8, 9 and 10, the rotary member carrying the fans 5 and 5' is pivoted on bearings 10' arranged at the ends of a fork support 22 secured to a standard 23. Said rotary member comprises a frame provided with a casing 24 in which are arranged an electric motor 25 and a counterweight 26 to balance the weight of the motor. Two pivots 27 are provided in the bearings 10' at the sides of said casing. Frames 28 and 28' carrying the fans 5 and 5' are secured each on one of said pivots.

Pulleys 29, 29' secured to the shaft of the motor 25 are connected by belts 42, 42' with pulleys 30, 30' fixed to the shafts of fans 5, 5', the rotation of the motor shaft being thus transmitted to the fans. The axis 38 of fan 5 is provided with another pulley 31 driving, by means of a belt 43, a pulley 32

pivoted in frame 28. Connected to said frame is a worm gear 33 driving a pinion 34 secured to shaft 35. The shaft 35 is pivoted in the rotating frame 28 and drives a pinion 36 which engages a stationary rim 37 secured in the bearing 10.

Owing to the arrangement described, the motor 25 when driving the fans causes the member comprising casing 24 and frames 10 28-28' to rotate as a whole in bearings 10', as the pinion 36 rolls on rim 37 and drives said member.

The electric current may be supplied to the motor by means of sliding contacts of 15 any suitable kind.

Should a single fan be sufficient, it may be secured directly to the motor shaft, the side frames 28 and 28' being dispensed with; in this case the fork support 22 must 20 obviously be of such a width as to allow the fan blades to pass between its arms.

The fan or fans being caused to rotate around a horizontal axis as described, the direction of the air stream or streams produced by said rotation is continually varied as shown in Figs. 2, 3, 4, 5 and 6, in which the air streams are shown to act on the material to be dried in different directions during the operation of the apparatus.

30 Furthermore the intensity of said air stream is continually varied during the revolution of the fans as shown in Figs. 2 and 5. In the position shown in Fig. 3, the full air stream is directed toward a single section 35 of the chamber and is therefore of a greater intensity; when the fans are in the position shown in Fig. 4 the air stream acts with full intensity on the material arranged near the fans; finally Figs. 5 and 6 show the fans 40 operating as described in connection with Figs. 3 and 2 respectively, the direction of the air current being reversed.

The described apparatus allows of ventilating in succession the two sections of a 45 chamber without stopping the fans, the direction of the air current being reversed without reversing the fans. Finally, all parts of the chamber are reached by the air current and the intensity of the air current varies in accordance with the direction 50 or heading of the fans. In drying chambers particularly in those for alimentary pastes it is often essential to have air currents continually varying in direction and intensity. 55 This, however, cannot be attained by known apparatus, which comprise a fan rotating about a stationary axis.

What I claim as new and desire to secure by Letters Patent is:—

60 1. A drying chamber for materials which must be suspended, comprising in combination means for hanging the material to be dried and means for generating an air current, said generating means being caused to rotate around a horizontal axis so that the

air current changes continually its radial direction from said horizontal axis.

2. A drying chamber for materials which must be suspended, comprising in combination means for hanging the material to be dried and means, arranged in different points of the chamber, for generating air currents, said generating means being caused to rotate around a horizontal axis so that each air current changes continually its radial direction from said horizontal axis. 75

3. A drying chamber for materials which must be suspended, comprising in combination means for hanging the material to be dried and means in the central portion of the chamber for generating an air current, said generating means being caused to rotate around a horizontal axis so that the air current changes continually its radial direction 80 from the said horizontal axis. 85

4. A drying chamber for materials which must be suspended, comprising in combination means for hanging the material to be dried and means in the central portion of the chamber for generating air currents, said generating means being caused to rotate around a horizontal axis so that each air current changes continually its radial direction 90 from the said horizontal axis. 95

5. A drying chamber for materials which must be suspended, comprising in combination supports for the material to be dried arranged in parallel rows, and means for generating an air current, said generating means being caused to rotate around a horizontal axis perpendicular to the supports for the material so that the air current changes continually its radial direction from 100 said horizontal axis. 105

6. A drying chamber for materials which must be suspended, comprising in combination supports for the material to be dried arranged in parallel rows and means for generating air currents, said generating means being caused to rotate around a horizontal axis perpendicular to the supports for the material so that each air current changes continually its radial direction from 110 said horizontal axis. 115

7. A drying chamber for materials which must be suspended, comprising in combination means for hanging the material to be dried, a fan, a support therefor, a member with a horizontal axis carrying said support and fan, and means for bodily rotating said support and fan around the axis of said member so that the air current generated by the fan changes continually its radial direction from said horizontal axis. 120

8. A drying chamber for materials which must be suspended, comprising in combination means for hanging the material to be dried, a fan, a support therefor, a member with a horizontal axis, mounted in the cen- 125 130

tral portion of the chamber, carrying said support and fan and means for bodily rotating the support and fan around the axis of said member so that the air current generated by the fan changes continually its radial direction from said horizontal axis.

9. A drying chamber for materials which must be suspended, comprising in combination means for hanging the material to be dried, a plurality of fans, supports for the same, a member with a horizontal axis carrying the supports and fans and means for bodily rotating said supports and fans around the axis of said member so that each air current generated by a fan changes continually its radial direction from the said horizontal axis.

10. A drying chamber for materials which must be suspended, comprising in combination means for hanging the material to be dried, a plurality of fans, supports for the same, a member with a horizontal axis, mounted in the central portion of the chamber, carrying said supports and fans and means for bodily rotating said supports and fans around the axis of said member so that each air current generated by a fan changes continually its radial direction from said horizontal axis.

11. A drying chamber for materials which must be suspended, comprising in combination means for hanging the material to be dried, a fan, a support therefor, a member with horizontal axis carrying said support and fan, a transmission for driving said fan, a pinion mounted on said member and driven by the transmission and a stationary toothed rim meshing with said pinion thereby causing said support and fan to bodily rotate about a horizontal axis.

12. A drying chamber for materials which must be suspended, comprising in combination means for hanging the material to be dried, a plurality of fans, supports therefor, a member with a horizontal axis carrying said supports and fans, a transmission for driving said fans, a pinion mounted on said member and driven by said transmission and a toothed rim meshing with said pinion thereby causing said supports and

fans to bodily rotate about the axis of said member.

13. A drying chamber for materials which must be suspended, comprising in combination means for hanging the material to be dried, a fan, a support therefor, a member with a horizontal axis carrying said support and fan, a standard carrying said member, a motor mounted on said member, a transmission driven by said motor and driving said fan, a pinion mounted on said member and driven by said transmission and a stationary toothed rim meshing with said pinion thereby causing said support and fan to bodily rotate about the axis of said member.

14. A drying chamber for materials which must be suspended, comprising in combination means for hanging the material to be dried, a plurality of fans, supports therefor, a member with a horizontal axis carrying the supports and fans, a standard carrying said member, a motor mounted on said member, a transmission driven by said motor and driving the fans, a pinion mounted on said member and driven by the transmission and a stationary toothed rim meshing with said pinions thereby causing said support and fans to bodily rotate about the axis of said member.

15. A drying chamber for materials which must be suspended, comprising in combination means for hanging the material to be dried, a fan, a support therefor, a frame with a horizontal axis carrying said support and fan, a motor mounted on said frame and adapted to drive said fan, a shaft mounted on said frame, a pinion secured to said shaft and driven by the motor and in turn driving the shaft, another pinion secured to said shaft and driven by same, and a stationary toothed rim meshing with said other pinion thereby causing said support and fan to rotate about the axis of said frame.

In testimony whereof I affix my signature in presence of two witnesses.
